[57] CLAIM

The ornamental design for a side element for a shoe upper, as shown and described.

DESCRIPTION

FIG. 1 is a side elevational view of a side element of a shoe upper showing my new design applied to one side of a shoe;

FIG. 2 is a side elevational showing the element applied to the opposite side of a shoe; and

FIG. 3 is a sectional view of the side element of a shoe upper taken generally along line 3—3 of FIG. 2; The broken line showing of a shoe upper and shoe sole, including the side panel portion below the lace eyelets of the shoe upper, is for illustrative purposes and forms no part of the claimed design.

FIG. 1
